UNITED STATES PATENT OFFICE

96,306

DESIGN FOR AN ELECTRIC RANGE OR SIMILAR ARTICLE

Max L. Goldbert, New York, N. Y., assignor to
Electric Trading Corporation, New York, N. Y.,
a corporation of New York

Application November 2, 1934, Serial No. 53,849

Term of patent 14 years

To all whom it may concern:

Be it known that I, Max L. Goldbert, a citizen of the United States, and a resident of the Borough of Manhattan, city, county, and State of New York, have invented a new, original, and ornamental Design for an Electric Range, or Similar Article, of which the following is a specification, reference being had to the accompanying drawing, forming a part thereof.

Fig. 1 is a perspective view of an electric range

or similar article showing my new design with the heating elements disposed against the body of the range;

Fig. 2 is a similar view thereof with the heating elements swung out from the cooking chamber.

I claim:

The ornamental design for an electric range or similar article, as shown and described.

MAX L. GOLDBERT.
